UNITED STATES PATENT OFFICE.

WILLIAM REYNOLDS, OF MANCHESTER, NEW HAMPSHIRE.

IMPROVEMENT IN LOOMS.

Specification forming part of Letters Patent No. 35,981, dated July 22, 1862.

To all whom it may concern:

Be it known that I, WILLIAM REYNOLDS, of Manchester, in the county of Hillsborough and State of New Hampshire, have invented certain new and useful Improvements in Picker-Motions for Looms; and I do hereby declare that the same are described and represented in the following specification and drawings.

To enable others skilled in the art to make and use my improvements, I will proceed to describe their construction and operation, referring to the drawings, in which the same letters indicate like parts in each of the figures.

Figure 1 is an elevation of one side of my improved picker-motion. Fig. 2 is a top view of the same. Fig. 3 is the reverse of Fig. 1, showing the opposite side.

The nature of my invention and improvements in picker-motions for looms consists in a grooved standard at one or both ends of the rail, (curved or otherwise,) for the purpose of holding the rocker on the rail when it is worked by the picker-staff to throw the shuttle, and in arranging a roller in the stand—that is, next to the side of the loom—so that the end of the rocker will work against and under it when the shuttle is thrown.

In the accompanying drawings, A is the end of the shaft on which the lay of the loom vibrates; or it may be the extension of a pivot, which answers the same purpose.

B is an iron rail, which may be made in the form shown, or in such other form as will answer the purpose. It is provided with a hub, C, at the side of one end, which is perforated to receive the shaft, on which it is fastened by the set-screws D and E, and the hole in the end of the hub farthest from the set-screws is made to fit the shaft, and the hole is widened in its perpendicular diameter gradually from that end to the other, as shown by broken lines F F in Figs. 1 and 3, so that by unscrewing one screw and screwing the other the outer end of the rail may be vibrated, either raised or lowered, and adjusted so as to make the rocker G and picker-staff H throw the shuttle at the proper pitch, either high or low, as may be desired.

The rail B is provided with a curved stand, I, at the outer end, with a groove, J, in it for the end of the rocker G to work in, while the opposite end of the rocker works in a groove in the stand K and works against the stand and roller L, as shown by broken lines in Figs. 1 and 3, and as the end of the rocker descends when the shuttle is thrown it works

under the roller L, so as to bring the curve M against the roller and partially under it. The roller L is arranged to turn on the pin N in the stand K, which stand may be made in the form shown in the drawings and fastened to the rail B by the screw P.

The picker-staff H, which is represented as broken off, may be drawn forward to throw the shuttle by a strap or link applied to it some distance above the rocker. The spiral spring S is fastened to the screw D and acts on the lever R to draw the picker-staff back after it has thrown the shuttle, being connected to the rocker by the strap Q.

In constructing this picker-motion the rocker and rail, or one of them, should be so curved that that part of the picker-staff which acts on the shuttle will traverse parallel or nearly parallel with the race-board of the lay of the loom, on which the shuttle traverses, and the end of the rocker which works against the roller or the stand should be so curved that the rocker will not slide on the rail as it is worked to throw the shuttle.

I have described the end of the hole next to the loom in the hub C as being made to fit the shaft; but this end may be widened and the opposite end made to fit the shaft, if preferred that way. Fig. 4 shows the hole in the hub C widened perpendicularly.

The above-described device for picker-motion is simple in its construction and operation, may be made cheap or at small cost, is not likely to get out of order, is easily adjusted to give the shuttle the desired inclination or pitch, and is easy of access to the attendant.

I believe I have described and represented my improvements in picker-motions for looms so as to enable any person skilled in the art to make and use them. I will now state what I desire to secure by Letters Patent.

I claim—

1. In combination with the rocker and rail, a grooved standard at one or both ends of the rail, curved or otherwise, for the purpose of holding the rocker on the rail when it (the rocker) is worked to throw the shuttle, substantially as described.
2. The roller L, in combination with the grooved stand K and rocker G, for the purpose set forth, substantially as described.

WILLIAM REYNOLDS.
